UNITED STATES PATENT OFFICE

CLARENCE HENRY VEALE, OF TULSA, OKLAHOMA, ASSIGNOR OF FORTY-NINE ONE-HUNDREDTHS TO MONROE O. MASON AND MILTON L. MASON, BOTH OF TULSA, OKLAHOMA

FLUSH TYPE THEFTPROOF PANEL BOARD

Application filed April 2, 1928. Serial No. 99,422.

This invention relates to an electrical apparatus, particularly to mountings for electric current meters and the switches and fuse blocks associated therewith, and has for its object the provision of a novel panel board or device for this purpose which may be set flush in the wall of a building and which will, moreover, be theft-proof so as to prevent unauthorized use of current or tampering with any of the interior mechanism by unscrupulous persons.

An important and more specific object is the provision of a mounting comprising a box-like casing adapted to be let flush into a wall and containing the fuse block and switch mechanism, the front of the casing being closed by a cover which provides a neat trim for the box and the electric light meter used in connection therewith, certain portions of the cover being capable of removal by the employees or other authorized persons connected with the electric light company, the removal of these elements, however, necessitating taking off certain seals which are provided by the company for its protection, it being quite obvious that the absence of these seals will be a clear indication that some one has been tampering with the mechanism.

Another object is to provide a device of this character in which the cover is provided with a door which may be readily opened by the user of the current so as to permit renewal of any of the fuses in case they become blown out as frequently happens.

An additional object is to provide a device of this character which in addition to being neat and attractive in appearance will be also simple and inexpensive in manufacture, easy to install, positive in its operation, efficient and durable in service and a general improvement in the art.

With the above and other objects and advantages in view, the invention consists in the details of construction and the arrangement and combination of parts to be hereinafter more fully described and claimed, and illustrated in the accompanying drawings, in which:

Figure 1 is a front elevation of the complete device.

Figure 2 is a vertical section taken on the line 2—2 of Figure 1, and

Figure 3 is an elevation of the box with the cover removed.

Referring more particularly to the drawings, I have shown the device as comprising a box or casing 10 constructed of any suitable material, preferably sheet metal and of any necessary size. This box or casing is adapted to be let into a wall so as to be flush with the surface thereof, and the front of the box is open and formed with a continuously extending flange 11 which provides an abutment for the cover or finish indicated generally by the numeral 12. Located at the front or open face of the box or casing is an auxiliary box structure 13 which is depressed inwardly as shown but which has its back wall portion 14 formed with spaced slots 14^a to permit access to fuses 15 mounted in the usual fuse block 16, it being well known that these fuses must be replaced in case they become broken or burned out from any cause. Within the auxiliary box structure 13 is a partition 17 defining a separate compartment 17^a the back of which is provided with an opening 18 permitting access to two other fuses 19 carried by the fuse block. Also located within the compartment 17^a is the control switch 20 which may be of any ordinary or preferred type and equipped with an operating handle 21 which extends through a suitable slot 22 in the front closure plate 23 which is of considerably greater length than the box 10 so as to have a portion 24 extending upwardly thereabove as clearly indicated in Figure 1. Securing members 25, such as screws or bolts pass through the front plate 23 and act to secure it together with the auxiliary box members to the flange 11 of the box 10.

Mounted at the upper portion of the cover plate 23 is a forwardly extending socket member 26 for the reception of the current meter 27 which is visible through an opening 28 in the extension 24 of the plate 23. That portion of the cover plate 23 formed with the slot 22, which portion is indicated by the numeral 29 is removable as is the socket member 26, and both are held in position by studs 30.

carrying wing nuts 31 tied together in pairs by rods 32 passing therethrough and carrying seals 33. Below the plate section 29 the plate 23 is formed with an opening 34 normally closed by a hinged door 35 which may be opened whenever it is necessary to have access to the fuses 15. It is of course understood that the plate section 29 is removed when it is necessary to have access to the mechanism of the switch and that the socket member 26 is removed when it is necessary to remove or repair the meter.

As an effective seal for the entire cover plate 23, I provide a stud 36 which extends through a suitable hole 37 in the plate 23 and which carries a seal 38.

In use, the device is operated in substantially the same manner as others of this general class, but it will be observed that it is theft-proof owing to the provision of the seals and securing devices for the various removable elements. Furthermore, the device possesses the great advantage of being flush with the surface of the wall to which it is applied and it is therefore neat and attractive in appearance in addition to having the other advantages specified. It is believed that the construction, operation and advantages will be readily apparent to one skilled in the art without further explanation.

While I have shown and described a preferred embodiment of the invention, it should be understood that I reserve the right to make such changes in the form, construction and arrangement of parts as will not depart from the spirit of the invention or the scope of the subjoined claims.

Having thus described the invention, I claim:

40 1. A cabinet for a flush type panel board, comprising a rectangular box like casing having an open front provided with an inwardly extended peripheral flange, the casing being adapted to be let into a wall with the open front substantially flush with the face of the wall, and an auxiliary frusto-pyramidal shell member located within the open front of said casing and having a peripheral outstanding flange overlying said first named flange, the back portion of said auxiliary shell member being provided with spaced slots, said shell member dividing the space within the casing into two compartments, access to the rear one of which may be had through said openings, 45 a partition element extending transversely of said auxiliary shell member and dividing it into separate compartments one for fuses and the other for a switch, a panel for closing the front of the box like casing, said panel 50 overlying the second named flange and secured thereto and to the first named flanges by securing elements introduced from the front and being formed with a plurality of openings, and means for closing said openings in the panel.

2. A device of the character described comprising a rectangular box-like casing having an open front provided with an inwardly extending peripheral flange and adapted to be recessed into a wall with the open front substantially flush with the face thereof, a substantially frusto-pyramidal shell member located within said casing and having a peripheral outstanding flange overlying said first named flange, the back of said auxiliary shell member being provided with spaced slots said shell member dividing the space within the casing into forward and rear compartments, fuse blocks located within the rear compartment and accessible through said slots, a partition element extending across said shell member and dividing said forward compartment into upper and lower sections, the back wall of the shell member within said upper section being formed with an opening, fuse blocks located within said rear compartment and accessible through said last named opening, a switch device located within said upper section, a panel overlying the front of the box and formed with openings permitting access to said upper and lower sections of the forward compartment, doors normally closing said last named openings, and securing elements passing through the panel and through said first and second named flanges for holding the casing, shell member and panel assembled.

In testimony whereof I affix my signature.

CLARENCE HENRY VEALE.
